UNITED STATES PATENT OFFICE

JAMES ROBERT LONGWORTH AND HERBERT HIRST, OF BOLTON, ENGLAND; SAID LONGWORTH ASSIGNOR TO SAID HIRST

AUTOMATIC FIRE ALARM

Application filed January 12, 1929, Serial No. 332,187, and in Great Britain May 25, 1928.

This invention relates to automatic fire alarms and utilizes a thermostatic device for closing an electric circuit, which will cause a bell to ring or give other notification, while facilities are provided whereby, for testing or other purposes, the electric circuit may be closed.

A feature of the present invention is that we can readily utilize an ordinary push button switch used in connection with an electric bell or other notification device and adapt it to serve also as an automatic fire alarm without detracting from the facilities of being manually operated.

Where there is no existing push button switch or where it is desirable to have the existing one replaced we then apply a slightly modified construction but still retain the advantage of manual operation.

In rooms where it is improbable that the switch will be frequently required to be operated by hand we may provide another modified type of our invention, providing in this case for a fine adjustment of the thermostatic device. In this case however we still provide an extension whereby the devices may be operated by hand.

In order that our invention may be fully understood we hereinafter describe same with reference to the accompanying sheet of drawings, in which:

Fig. 1 is a side sectional view showing a form of fire alarm and bell push switch constructed in accordance with our invention.

Fig. 2 illustrates a further modification of our invention.

Fig. 3 is a front view of the devices shown in Fig. 2.

In constructing our device in accordance with Fig. 1 we provide a base 3^b of insulating material carrying the usual normally spaced apart contacts 8 and 8^a connected respectively to the wires 10 and 9. An annular member 3^c is then threaded at one end into the base 3^b and supports a casing 2. This annular member is internally screwthreaded to accommodate the threaded disc 11. Through an orifice in this disc extends a spring actuated plunger 12 which has a flange 13 at one end and a washer 14 at the other. We insert a

screw 15 into the end of the plunger adjacent to the contacts 8^a and 8 for actuating the former into contact with the latter. A screw 16 is fixed in the other end of the plunger 12 and forced into contact with the part 4^c of a thermostat by the spiral spring 12^a.

The thermostat may be constructed of any known type but preferably consists of two metal discs 4^a, 4^b joined at their edges with a volatile liquid such as alcohol between them. Extending from the disc 4^a is a projection 5 to which is secured a push button 6 which protrudes freely through the casing 2 which is preferably detachably mounted on the member 3^c through the medium of the screws 2^b, said casing 2 preferably having perforations 2^a therethrough.

By pressing the button 6 the plunger 12 is moved inwardly against the action of the spiral spring 12^a and the screw 15 forces the contact 8^a into engagement with the contact 8, thus closing the electric circuit through the wires 9 and 10, the device thus functioning as an ordinary bell push switch.

However, when a fire occurs, or when through other causes heat is generated in the vicinity, the liquid in the thermostat expands, causing the disc 4^b to move away from the disc 4^a with the result that the plunger 12 is moved inwardly as above described and the electric circuit closed, giving an alarm.

By removing the casing 2 the disc 11 can be screwed in or out on the member 3^c to vary the tension of the spring 12^a so that when the device functions through the medium of the thermostat it will be actuated at varying temperatures to give the alarm. This is due to the different tensioning of the spring giving more or less resistance to the movement of the disc 4^b on expansion.

The modified device depicted in Figs. 2 and 3 functions in the same manner as referred to above, but, in this instance, the casing 2 covers the push button 6. An adjusting screw stud 5^a is threaded through the casing 2 and engages the push button 6. A pointer 5^b is secured to the exposed end of this stud 5^a and extends over suitable graduations 5^c on the casing 2. Although this modified form of device is intended for use where it is not

desired to employ it as an ordinary push button switch, yet the circuit may be closed by turning the pointer 5^b until the contacts 8^a and 8 are forced into engagement.

- 5 The normal purpose of the stud 5^a and pointer 5^b is, however, to vary the tension of the spring 12^a, so that the device will function under the influence of the thermostat at variable temperature, depending upon the 10 setting of the point. Screwing in the stud 5^a compresses the spring 12^a causing it to offer greater resistance to the movement of the disc 4^b on expansion. When the stud 5^a is screwed in the reverse direction the opposite effect takes place.

15 Such being the nature and object of our said invention what we claim is:—

- 20 1. In an automatic fire alarm, in combination, a base, normally spaced apart electric circuit contacts on said base, an expansible thermostat, a plunger, including a spring, interposed between the thermostat and the contacts, said plunger adapted to force one contact into engagement with the other upon 25 expansion of the thermostat and acting against the action of the spring, a casing enclosing the contacts, thermostat and plunger, and a longitudinally adjustable disc in the casing for varying the tension of the 30 plunger spring.

- 25 2. In an automatic fire alarm, in combination, a base, normally spaced apart electric circuit contacts on said base, an expansible thermostat, a plunger, including a spring, interposed between the thermostat and the contacts, said plunger adapted to force one contact into engagement with the other upon expansion of the thermostat and acting against the action of the spring, a casing enclosing the contacts, thermostat and plunger, a longitudinally adjustable disc in the casing for varying the tension of the plunger spring, and means extending exteriorly of the casing for varying the tension of the plunger 40 spring to offer varying resistance to the movement of the thermostat under expansion.

- 45 3. In an automatic fire alarm, in combination, a base, normally spaced apart electric circuit contacts on said base, an expansible thermostat, a plunger, including a spring, interposed between the thermostat and the contacts, said plunger adapted to force one contact into engagement with the other upon expansion of the thermostat and acting 50 against the action of the spring, a casing enclosing the contacts, thermostat and plunger, and means extending exteriorly of the casing for varying the tension of the plunger spring to offer varying resistance to the movement of the thermostat under expansion.

- 55 4. In an automatic fire alarm, in combination, a base, normally spaced apart electric circuit contacts on said base, an internally threaded member attached to said base, a 60 longitudinally movable disc threaded into

said member, a plunger longitudinally movable in said disc, a spring for normally holding said plunger from the actuated position with respect to the contacts, an expansible thermostat in engagement with one end of the plunger, a casing attached to the internally threaded member, and a push button carried by the casing and connected to the thermostat.

5. In an automatic fire alarm, in combination, a base, normally spaced apart electric circuit contacts on said base, an internally threaded member attached to said base, a longitudinally movable disc threaded into said member, a plunger longitudinally movable in said disc, a spring for normally holding said plunger from the actuated position with respect to the contacts, an expansible thermostat in engagement with one end of the plunger, a casing attached to the internally threaded member, a push button carried by the casing and connected to the thermostat, a screw stud threaded through the casing, graduations on the exposed face of the casing and a pointer secured to the screw stud.
